COMBINATION ELECTRIC COOKER AND SUPPORT STAND THEREFOR FOR BROILING AND BARBECUING FOOD

Cecil L. McLaren, 366 S. Minnesota,
Wichita, Kans. 67211

Filed May 27, 1968, Ser. No. 12,101

Term of patent 14 years

Int. Cl. D7—04

U.S. Cl. D81—10

FIG. 1

FIG. 2

FIG. 3

FIG. 4

FIG. 5

FIG. 6

FIG. 7

FIG. 8

FIG. 9

FIG. 10

I claim:

The ornamental design for a combination electric cooker and support stand therefor for broiling and barbecuing food, substantially as shown and described.
